Stephen & Daniel Young

Letters Patent. Issued December 10, 1808

The Schedule annexed to the Letters Patent making
part of the same, containing a description in the words of the said
Stephen & Daniel Young their selves, their manner for
rolling & heating iron & cutting Nails. —

The dimensions of the following may be varied. The frame for
the rollers to be made of cast iron, the rollers to be from 14
to 18 inches in length, between the centers of 18 to 24
inches in circumference to be made with iron of strength
turned off & counter sinks with a cross in them so as to raise
the nail on the nail on both edges before it goes into the
Cutter, which ought to be varied for nails & bands of any size.
The water wheel for cutting to be from 45 to 60 feet in circumference
as the heads of full of the water may require, so shaft to be
from 9 feet to 3 $\frac{1}{2}$ in diameter, as the size of nail & bands
may require in diameter & from 10 to 20 feet in length so to have
one turned & made as a cast iron as the shaft to be smooth
rounds with as many bands on the shaft as may fit sizes of
nails. Each band to be turned on the shaft, so as to
have a edge put up with a dovetail & bands from 6 to 19
inches between according to the sizes of the nail & to went
so as to lead & point each other half opposite ways.
They have a beam made of iron & steel 14 by 16 inches treated
as far in length as the shaft as the quality of band will
allow for different sizes of nail & bands. — The water wheel to
be turned by vibration of the water within or without the
vibration, or cast iron by water or a weight. —
